UNITED STATES PATENT OFFICE.

JOHAN R. BAKSTAD, OF CHICAGO, ILLINOIS.

CRUSHER.

Application filed October 1, 1923. Serial No. 665,803.

To all whom it may concern:

Be it known that I, JOHAN R. BAKSTAD, a citizen of the United States, residing at Chicago, in the county of Cook and State of Illinois, have invented certain new and useful Improvements in Crushers, of which the following is a specification.

This invention relates to crushers.

There are many different types of stone crushers, all of which may be used with a degree of success for producing road material which will pass through a one inch ring, as required by highway departments of many States. However, some types of crushers produce too large a proportion of dust and fine particles; others can treat only comparatively fine stone or cannot crush hard stone. Most crushers in use produce a percentage of over-size, making necessary, screening and recrushing. Again many types of crushers are unable to produce an appreciable capacity when crushing to a fine product, or the machine is designed to such dimensions that the price of same is prohibitive for the nature of work in question.

Probably the most successful arrangement for securing the desired results is a combination of crushers, such as a jaw crusher for primary breaking, and a disk crusher for secondary breaking. This arrangement, however, in addition to the cost of two machines, requires the introduction of sizing screens for the separation of products from primary to secondary units and, usually, also equipment for conveying same.

It being frequently desirable that the entire combination be portable, it will be appreciated that a single unit, capable of performing properly, is much in demand.

There is, and has been for some years, a growing demand for a crusher that will produce in one operation, or with a single unit, a crushed product that will pass through a one inch ring, from stone or gravel boulders ranging in size from four to six inches, and up.

Accordingly, one object of my invention is to provide a simple, durable, efficient and relatively inexpensive unitary stone crusher adapted to overcome the above mentioned disadvantageous and undesirable features and adapted to successfully meet all of the requirements demanded under service conditions.

Another object is to provide a stone

crusher of the above mentioned characteristics which is of a readily portable nature.

These and other objects are accomplished by means of the arrangement disclosed on the accompanying sheet of drawings, in which—

Figure 1 is a fragmentary vertical sectional view through a stone crusher embodying the preferred form of my invention; and

Figures 2, 3, 4 and 5 are similar fragmentary vertical sectional views of modifications of my invention.

The various novel features of my invention will be apparent from the following description and drawings and will be particularly pointed out in the appended claims.

Manufacturers of jaw type crushers have often attempted to produce the desired results in crushing with veriformed dies, the most recent form for fine crushing having a flat crushing surface at the bottom of both stationary and movable dies. However, the jaws can only be made to close to approximately one-fourth of an inch due to the rough cast die surfaces, and with a jaw movement ranging from five-eighths of an inch to three-fourths of an inch considerable "slip through" occurs in which the product will not pass through a one inch ring. In addition, the capacity is very much reduced. It is found even under the circumstances above mentioned, there is a small percentage of large enough size to require a two and one-half inch ring. One reason for the "slip through" is the size of corrugations in the dies, but a coarse corrugation is more satisfactory, in fact necessary, when crushing boulders or rock of the size for which various crushers are designed.

It is my conclusion that the jaw type of crusher is superior in action to all other types and further that fine crushing can be successfully accomplished with jaw members if the crushing surface be materially increased as the stone is gradually broken up or, in other words, a double path or outlet for fine material be provided. Based upon this theory, the present design has been produced by which a standard jaw crusher of any size may be built as a reduction crusher by the introduction of a secondary jaw member interposed between the regular jaw members.

Referring first to Figure 1 of the drawings, it will be noted that my invention is

disclosed in connection with a jaw type of crusher having a stationary jaw 10 and a cooperating movable jaw 11, the latter of which is pivotally mounted at its upper end on a shaft 12 for a purpose to be described later. The stationary jaw is provided with stationary jaw die 14 and the movable jaw member is provided with a die 15. The movable jaw is actuated from a main drive shaft 16, through a tumbler shaft 17, tumbler arbor 18 and toggle 19, one end of which toggle is carried in a toggle seat 20 associated with the tumbler arbor and the other end of the toggle being mounted in a similar toggle seat 21 carried by the movable jaw 11. A properly anchored spring rod 22 connected to the movable jaw 11 holds the toggle 19 against displacement.

Heretofore, stone fed between the jaw dies 14 and 15 have been subjected to a crushing action, but as stated hereinabove there has been considerable "slip through" which will not pass through a one inch ring. In solving the problem of crushing stone to smaller size and in the proper quantity, I have provided what may be termed a secondary swinging jaw 23 arranged below the primary jaws and having oppositely arranged stone crushing surfaces or dies 24 and 25, respectively, which cooperate with auxiliary or secondary dies 26 and 27, respectively carried at the lower ends of movable jaw 11 and stationary jaw 10 respectively. In this way two additional and separate crushing mouths are provided. The auxiliary die 27 is seated at 28 in the stationary jaw and is clamped to said seat by a wedge shaped clamping member 29 secured to the stationary jaw by a bolt 30, the clamping member 29 also acting as a seat or support for the stationary die 14 which is otherwise secured to the jaw 10 by a clamp 13. Similarly, the secondary jaw die 26 is held in place by a clamp 31, which also forms a seat for the die 15 carried by the movable jaw 11, the upper end of the die 15 being clamped in place by a wedge shaped clamping member 32.

The design is so worked out that the opening between the regular jaw dies 14 and 15 is always approximately twice the area of each opening of the secondary crusher mouths or equal to the combined area of the two. In other words, with an opening of two inches between the regular or primary dies 14 and 15, there will be an opening of only one inch between each set of secondary jaw dies, but the width is the same for all three sets of dies. This relation will remain the same when changing the jaw opening between the regular dies, because the secondary jaw 23 is caused to swing in unison with the primary movable jaw 11 but the relationship may be changed as described hereinafter. To accomplish this re-

sult the upper end of the secondary swinging jaw is pivotally mounted upon a pin or shaft 33 and the lower end of the secondary swinging jaw is connected by a link 34 to a pin 35 carried near the lower end of the movable jaw 11.

It will be noted that the shaft 33 upon which the secondary swinging jaw is mounted is an eccentric shaft, so that the openings between the secondary swinging jaw and its associated secondary dies may be equalized, if necessary, or to vary the smaller openings with relation to the regular jaw opening for which it may be set. For facilitating this adjustment it will be noted, also, that the pin 35 to which link 34 is connected also has an eccentric shaft. The opening between the primary jaw dies is varied by means of length of toggle 19.

As shown, the secondary swinging jaw 23, which is mounted between the main jaws and more particularly between the secondary die members carried by the main jaws, preferably is wedge or bell shaped so that the secondary mouth openings gradually narrow toward the lower or exit ends thereof. The upper end of said jaw is preferably pointed as at 9 and flared for controlling a division of the flow of crushed material. As shown in Figure 1, the secondary swinging jaw member, is pivoted at its upper end, but, as will be pointed out hereinafter, said secondary swinging member may be pivotally supported at its lower end.

The lower or secondary dies 26 and 27 may be separate or cast in one piece with the regular or primary dies, but by making all dies separate the primary dies are reversible end for end for double wear, as at present, and the secondary dies are not only reversible but interchangeable between the stationary and movable jaws. With separate jaws the same may be easily and quickly clamped in place as hereinabove described, it being noted that the clamps 29 and 31 serve the double purpose of clamping the secondary dies and seating the primary dies.

In Figure 2 of the drawings an arrangement is shown in which the primary and secondary dies are cast in a single piece as shown at 36 and 37 respectively. Also there is shown a baffle plate 38 for guiding the discharge from the main portion of the jaw dies to the secondary jaw dies portions.

When stone is crushed between the primary jaws, same being closed as in ordinary practice to from 1 to 2 inch opening, the product is broken up fine enough to enter the secondary jaws on both sides of the intermediate swinging jaw.

In Figure 3 an arrangement is shown in which the secondary swinging jaw 39 is pivotally mounted eccentrically on a pin 40 at its lower end so that, when free to swing as a result of its own weight during

the outward movement of the main swinging jaw 41, the secondary swinging jaw 39 may swing to the left to maintain equal mouth openings 42 and 43. The secondary swinging jaw member is limited in such swinging movement by an adjustable stop member 44.

A similar arrangement is shown in Figure 4, which shows, however, the primary and secondary dies 45 and 46 cast integrally, and a spring 46^a for assisting gravity in moving the intermediate jaw in one direction.

With a regulating stop provided for the intermediate swinging jaw to stop its movement in a central position between the secondary die surfaces when the primary moving jaw opens to the end of its stroke, it is seen that the stone which has entered from above will be crushed on both sides of the intermediate jaw by virtue of the power being transmitted from the primary moving jaw through the stone on both sides of the intermediate jaw to the stationary jaw. If the opening at the bottom of the regular die is two inches, and the jaw movement at this point is three-fourths of an inch, the opening between each set of secondary dies would be approximately one inch, and the jaw movement for each secondary mouth slightly more than three-eighths of an inch, or, little more than one-half of the primary movement, since the primary moving jaw is swung from the top, and the distance traveled increases toward the bottom.

To make the secondary crushing action definitely positive, the intermediate jaw may receive its movement and crushing power independently through connecting rods or toggles transmitting power from the main shaft or cam. This may be accomplished with a connection from the tumbler provided with a second toggle seat for a shorter motion, or a connection from the primary swinging jaw arranged in a manner to transmit to the intermediate jaw only one-half of the full movement of the primary swinging jaw. The latter arrangement being preferable, is shown in Figure 1 of the drawings. With this arrangement the regulating stop, as shown in Figures 3 and 4, becomes unnecessary. Also, the modified arrangement shown in Figure 5 becomes unnecessary, said latter arrangement including a secondary swinging member 47 which is yieldably held in a central position by two springs 48 and 49 operating between suitable abutments 50 and 51 respectively and a depending portion 52 extending downwardly from the member 47.

In certain figures of the drawings and particularly as shown in Figure 1, a design is provided with a link or toggle 34 connecting the primary and intermediate jaws which by virtue of the two point suspension

of these parts and by offsetting the link centers, transmits the desired motion and power to the secondary crusher mouths. As pointed out hereinabove the intermediate jaw is suspended from an eccentric shaft 33, in addition to which the connecting link is also provided with an eccentric shaft 35 for adjustment, so that it is possible and a simple matter to regulate the openings to suit requirements.

By means of this crusher it is possible to produce in one operation, the commercial one inch product required, and with a capacity substantially equivalent to the same size standard crusher when turning out a two inch product.

It is my intention to cover all modifications of the invention falling within the spirit and scope of the following claims.

I claim:

1. In a crusher, the combination of a plurality of cooperating relatively movable jaw members between which stone is given a primary crushing in a single path, and means movable with one of said other jaw members and cooperating with said jaw members for giving said stone a secondary crushing in a plurality of paths.

2. In a crusher, the combination of a plurality of cooperating relatively movable jaw members between which stone is crushed, and means in a plane intermediate said jaw members and movable with one of same and cooperating with said jaw members for giving the stone a secondary crushing.

3. In a crusher, the combination of a plurality of relatively movable jaw members between which stone is crushed in a single path, and movably mounted means in a plane intermediate said jaw members cooperating with the latter for giving the stone a secondary crushing.

4. In a crusher, the combination of a stationary jaw member, a pivotally mounted jaw member cooperating with said stationary jaw member for crushing stone, and means pivotally mounted in a plane between said stationary and movable jaw members and cooperating therewith for giving the stone a secondary crushing.

5. In a crusher, the combination of a stationary jaw member, a pivotally mounted jaw member cooperating with said stationary jaw member for crushing stone, and pivotally mounted means in a plane intermediate said stationary and movable jaw members for giving the stone a secondary crushing.

6. In a crusher, the combination of a stationary jaw member, a movable jaw member cooperating with the stationary jaw member for crushing stone, and a second movable jaw member in a plane intermediate said stationary and other movable jaw members for giving stone a secondary crushing.

7. In a crusher, the combination of a plurality of relatively movable spaced jaw members between which stone is crushed, and an additional jaw member spaced from the other two movable in unison with one of said aforesaid jaw members for controlling the size of the openings between said additional and other aforesaid jaw members.
8. In a crusher, the combination of three relatively movable spaced jaw members between which stone is crushed, certain of said jaw members being movable in unison for controlling the size of the openings through which the stone passes and one of said jaw members being located in a plane intermediate the other two jaw members.
9. In a crusher, the combination of two primary and one secondary relatively movable jaw members arranged whereby stone is crushed in a single primary path and in two secondary paths, one primary and the secondary of said jaw members being connected for simultaneous actuation.
10. In a crusher, the combination of a stationary jaw member, a movable jaw member cooperating therewith for crushing stone, and a third jaw member cooperating with said other jaw members for giving the stone a secondary crushing, said third jaw member being movable with said other movable jaw member for controlling the size of openings between said jaw members, and means for varying the size of said openings.
11. In a crusher, the combination of a stationary jaw member, a movable jaw member cooperating therewith for crushing stone, and a third jaw member cooperating with said other jaw members for giving the stone a secondary crushing, said third jaw member being movable with said other movable jaw member for controlling the size of openings between said jaw members, and an additional jaw member for controlling the size of openings between said jaw members, and eccentric means for varying the size of said openings.
12. In a crusher, the combination of a stationary jaw member, a movable jaw member cooperating therewith for crushing stone, a third jaw member cooperating with said other jaw members for causing a secondary crushing of the stone, and a link connecting said third jaw member and said movable jaw member whereby said jaw members may move in unison.
13. In a crusher, the combination of a stationary jaw member, a movable jaw member cooperating therewith for crushing stone, and a third jaw member interposed between said other jaw members for giving stone a secondary crushing action, and an eccentric mounting for said third jaw member whereby relative jaw openings may be controlled.
14. In a crusher, the combination of a stationary jaw member, a pivotally mounted jaw member cooperating with said stationary jaw member for crushing stone, a third jaw member cooperating with said other jaw members for giving stone a secondary crushing, a link connecting said third jaw member and the pivotally mounted jaw member, the connection between said jaw members including an eccentric shaft, said third jaw member being mounted upon an eccentric shaft, and the main pivotally mounted jaw being mounted upon an eccentric shaft whereby the jaw members may have a relative swinging movement and the jaw openings controlled.

Signed at Chicago, Illinois, this 26th day of September, 1923.

JOHAN R. BAKSTAD.
